UNITED STATES PATENT OFFICE.

PATRICK K. O'LALLY, OF BOSTON, MASSACHUSETTS.

DOOR-SPRING.

SPECIFICATION forming part of Letters Patent No. 249,253, dated November 8, 1881.

Application filed February 9, 1881. (No model.)

To all whom it may concern:

Be it known that I, PATRICK K. O'LALLY, of Boston, in the county of Suffolk and State of Massachusetts, have invented certain Improvements in Door-Springs, of which the following is a specification.

This invention has for its object to provide certain improvements in springs for automatically-closing doors or equivalent hinged bodies, whereby cheapness, strength, simplicity, and effectiveness and convenience of operation are combined to a greater degree than heretofore. The invention consists in a spring composed of a single elastic metal rod or section of stout elastic wire having one end formed as a pivot, combined with supporting brackets adapted to be attached, respectively, to the door and casing, and provided with sockets adapted to receive the opposite ends of the spring, the pivot end of the spring being journaled in the bracket on the casing, so that the spring can swing horizontally with the door, all as hereinafter specified and claimed.

Of the accompanying drawings, forming part of this specification, Figure 1 represents a side elevation of a portion of a door and its casing provided with a spring embodying my invention. Figs. 1^a, 1^b, and 1^c represent modifications. Fig. 2 represents a similar elevation, showing a different form of spring. Figs. 3 and 4 represent top views of the devices shown respectively in Figs. 1 and 2. Figs. 3^a and 4^a represent, respectively, sections on lines x x and y y, Figs. 3 and 4. Fig. 3^b represents a section on line x' x', Fig. 3. Fig. 5 represents a side view, and Figs. 6, 7, and 8 top views, of my improved spring adapted to outside window blinds or shutters. Fig. 9 represents a modification of my invention.

The same letters of reference indicate the same parts in all the figures.

In the drawings, D represents a door, and C the casing or jamb thereof.

a represents the spring, which is composed of a rod of suitably-elastic metal, preferably steel. This rod may be a section of stout steel wire, and is preferably curved in semicircular form when in its normal position, as hereinafter described.

b' represents an arm or bracket adapted to be attached to the door-jamb and project there-

from, so that its outer end will be outside of the axial line of the hinges of the door. One end of the spring a is formed as a pivot, and is journaled in a vertical socket, i, in said bracket, so that the spring may swing horizontally with the door, the pivot end of the spring and the socket being threaded to prevent the spring from being accidentally withdrawn from the socket.

b represents an arm or bracket, adapted to be attached to a door and project therefrom a suitable distance—say one or two inches. In the outer end of the bracket b is a socket, e, formed to receive the opposite end of the spring a. Said socket is preferably a countersunk depression made in the end of a screw, f, working in a threaded orifice in the bracket b, and enabling the socket to be adjusted to vary the tension of the spring a; but in case it is not desirable to vary the tension, the socket e may be formed directly in the side of the bracket b, as shown in Fig. 1^a. The socket e is so arranged that the spring is engaged with the socket wholly by its own resilience; hence the spring can be readily disconnected from the bracket b by merely springing it to increase its curvature, so that its end will slip out from the socket e, said end being bent outwardly, as shown at o, to enter the socket e.

When, on account of limited space or for any reason, it is desirable to place the brackets b b' nearer together I make use of the modification shown in Fig. 1^c, the spring a in this case having a loop, a', formed in the center thereof. This diminishes the horizontal space between the ends of the spring, while at the same time the spring being carried higher, its force is preserved and equally effective action secured; and this form of spring is especially useful when my invention is applied to outside blinds or shutters, as hereinafter described.

My invention operates as follows: When the door is closed and the spring is in its normal position the ends of the spring bear or press in opposite directions against the sockets in the brackets b b', and thus tend to keep the door closed. When the door is opened the spring swings on the bracket b', and its ends are brought nearer together the farther the door is opened, thus increasing the pressure of said ends on their brackets, so that when the door

is released the spring, in its effort to regain its normal position, will close the door.

It will be seen that the spring is extremely simple and effective.

- 5 By forming one end of the spring as a pivot and journaling it on the bracket b' , and by bending outwardly the opposite end of the spring and inserting it directly in the socket e , I avoid the expense of intermediate parts to connect the ends of the spring to their respective brackets. The provision of the socket-screw f for varying the tension of the spring enables it to be readily adapted to the weight of the door.
- 15 I do not limit myself in all cases to the U-shaped spring having one end formed as a pivot and bent outwardly at the other end to enter the socket in the bracket b , for the bracket b , with its lateral socket e , may be employed with 20 a spring that is approximately straight, as shown in Figs. 2 and 3, the bracket b' having a block, b^2 , pivoted to it provided with a vertical slot-shaped socket adapted to receive one end of the spring. The opposite end of the 25 spring enters the socket e , as in the form previously described. Neither do I limit myself in all cases to the employment of the lateral socket e in the bracket b , for in case it is not desirable to make the spring detachable from 30 the bracket b the socket of said bracket may be vertical, as shown in Fig. 1^b.

My improved spring may be applied to outside window blinds or shutters, as shown in Figs. 5, 6, 7, and 8. In Figs. 6, 7, and 8 are 35 represented plan views, the blind being closed, half-way open, and entirely open in the figures, respectively. A bracket or arm, b , being attached to the blind E , and a bracket, b' , to the window-casing F , the spring a is then applied 40 to the brackets in the manner previously described. In thus applying my spring to blinds or shutters I adjust the brackets b b' so that the spring, as it swings horizontally upon the bracket b' , is eccentric with the axial line of 45 the blind. Thus, when the pivots of the blind and the end of the spring which is attached to the bracket b are brought into the same plane by the swinging of the blind on its hinges, as shown in Fig. 7, the action of the spring is 50 neutralized; but when the blind is swung past this point the spring acts as a lever to open or

close the blind, as the case may be. In the drawings the spring is neutralized when the blind is swung half-way open; but by adjusting the bracket b' the spring may be neutralized at any desired point as the blind swings, and so made to act to throw the blind back beyond that point.

When my spring is similarly applied to a door it may be made to force the door back 60 when opened to any desired point, and allow the door to be freely swung to and fro without closing, up to said point, or to close it when swung beyond said point.

I also employ the modification of my invention shown in Fig. 9, the spring a in this case being straight and formed into a spiral, t , in the center.

I may here remark that it is not new to provide a door with an elliptical spring arranged 70 in a vertical or horizontal plane, said spring being composed of a number of leaves secured at one end in a pocket fixed to the door, and at the other end in a pocket jointed or hinged to the casing or jamb. My invention differs 75 from this, in that I employ a spring consisting solely of a single rod of wire, the bearings for both ends of which are preferably rigid or fixed.

Having described my invention, what I 80 claim is—

1. The combination of a spring composed of a single elastic rod or wire, a , having one end formed as a pivot, the bracket b' , provided with a socket receiving and permitting the rotation of the pivot end of the spring, and the bracket b , adapted to support the opposite end of said spring, as set forth.

2. The combination of the bracket b' , the spring a , pivoted at one end to said bracket, 70 and the bracket b , having the adjustable screw f , containing the spring-receiving socket e in its end, and adapted to regulate the tension of the spring, as set forth.

In testimony whereof I have signed my name 95 to this specification, in the presence of two subscribing witnesses, this 3d day of February, A. D. 1881.

PATRICK K. O'LALLY.
